UNITED STATES PATENT OFFICE

160,022

LICENSE PLATE EMBLEM

Henry P. Schindler, New Orleans, La.

Application February 3, 1950, Serial No. 7,724

Term of patent 7 years

(Cl. D14—6)

To all whom it may concern:

Be it known that I, Henry P. Schindler, a citizen of the United States, residing at New Orleans, in the parish of Orleans, and State of Louisiana, have invented a new, original, and ornamental Design for a License Plate Emblem, of which the following is a specification; reference being had to the accompanying drawing forming part thereof.

The dotted line showing is for illustrative purposes only.

I claim:

The ornamental design for a license plate emblem, as shown, and described.

HENRY P. SCHINDLER.
